UNITED STATES PATENT OFFICE.

JOHN M. G. STOLK, OF ENSLEY, ALABAMA.

BOX.

1,116,752.

Specification of Letters Patent. Patented Nov. 10, 1914.

Application filed October 31, 1913. Serial No. 798,505.

To all whom it may concern:

Be it known that I, JOHN M. G. STOLK, a citizen of the United States, residing at Ensley, in the county of Jefferson and State of Alabama, have invented certain new and useful Improvements in Boxes, of which the following is a specification.

This invention relates to receptacles and more particularly to boxes having for its primary object to provide a plurality of sections which are relatively adjustable in order to facilitate the dispensing of the contents.

A further object is to provide a device of this character comprising but a few simple parts which are readily associated for bringing about the desired result.

Other objects as well as the nature, characteristic features and scope of my invention will be more readily understood from the following description taken in connection with the accompanying drawings and pointed out in the claims forming a part of this specification.

Referring to the drawings:—Figure 1 is a side elevation of the device constructed in accordance with my invention; and Fig. 2 is a longitudinal sectional view taken on the line 2—2 of Fig. 1.

In the drawings wherein is illustrated the preferred embodiment of this invention, a receptacle or box 5 is provided which comprises a lower section 6 and an upper section 7, each of said sections being preferably of a cylindrical configuration, the lower of which has a girth less than that of the section 7 in order to allow for the telescoping of the section 6 within the section 7. The lower edge of the section 6 is preferably extended slightly outwardly as indicated at 8 and inwardly at right-angles to the body as indicated at 9 whereby to provide an annular ring or supporting member with which is engaged a bottom 10, said bottom

snugly engaging in the offset portion 8 of the section 6 and being held therein from movement. A horizontal bead 11 is formed on the section 6 spaced from the upper marginal edge thereof such as by striking a portion of the body outwardly as shown to advantage in Fig. 2.

The section 7 has the opposite ends thereof open and is provided with a horizontal bead 12 which is formed by striking a portion thereof inwardly, the bead 12 engaging the outer periphery of the section 6 while the

bead 11 engages the inner periphery of the section 7. Detachably arranged on the outer end of the section 7 is a cover 13 which is likewise of a configuration conforming to that of the section 7 and is formed by turning the marginal edges 14 thereof at right-angles to the body for engagement with the outer periphery of the section 7 adjacent the upper end thereof.

The structure as disclosed has several advantages over boxes appropriated for similar uses, such as tobacco boxes, in that the magnitude of the box may be reduced as the contents diminishes. This is accomplished, in a practical way, by having the lower section 6 telescoped within the upper section 7 and by the frictional engagement of the beads 11 and 12 with the faces of the complementary sections. That portion of the section 6 above the bead 11 and that portion of section 7 below the bead 12 prevents any material disalignment of the two sections, which are normally co-axial, by coming in contact with the complementary sections should a force be applied to the sections which might cause them to become distorted. The cover 13 preferably telescopes the section 7, and, as shown in the drawing, the section 6 is preferably in height greater than the section 7, so that, even when the material is disposed wholly within section 6, the covers 13 may be removed by merely moving one section relative to the other to reduce the magnitude of the box. If the contents of the box extend above the upper marginal edge of section 6, the cover is removed by the telescoping action, through its engagement with the contents. If the contents of the box is below the upper marginal edge of section 6, then this edge engages the under side of the cover and forces it from section 7 as one section is moved relative to the other as hereinbefore described.

I claim:

1. A receptacle comprising a lower section having a bottom and an upper section, the lower section being in height greater than the upper section and the former telescoping within the latter; and, a removable cover for said upper section positioned to be removed by engagement of the upper marginal edge of said lower section therewith upon sliding one section relative to the other, substantially as and for the purpose set forth.

2. In a receptacle of the character described, the combination of a lower section having a bottom; an upper section, the lower section telescoping within said upper section; a horizontal bead carried by said lower section at its outer face, spaced apart from the upper marginal edge to frictionally engage the internal periphery of said upper section; and, a horizontal bead carried by 10 said upper section at its inner face, spaced apart from the lower marginal edge thereof to frictionally engage the external periphery of said lower section below said first mentioned bead, substantially as and for the 15 purpose set forth.
3. In a receptacle of the character described, the combination of a lower section having a bottom; an upper section, the lower section telescoping within said upper section; a horizontal bead carried by said lower section at its outer face, spaced from the upper marginal edge to frictionally engage the internal periphery of said upper section; and a horizontal bead carried by 20 said upper section at its inner face, to fric- 25

tionally engage the external periphery of said lower section below said first mentioned bead, substantially as and for the purpose set forth.

4. In a receptacle of the character de- 30 scribed, the combination of a lower section having a bottom; an upper section, the lower section telescoping within said upper section; a horizontal bead carried by said lower section at its outer face to frictionally 35 engage the internal periphery of said upper section; and, a horizontal bead carried by said upper section at its inner face, spaced above the lower marginal edge thereof to frictionally engage the external periphery 40 of said lower section below said first mentioned bead, substantially as and for the purpose set forth.

In testimony whereof I affix my signature in presence of two witnesses.

JOHN M. G. STOLK.
